ROBERT J. JORDAN, OF NEW YORK, N. Y.

Letters Patent No. 88,488, dated March 30, 1869.

IMPROVEMENT IN PIANO-LOCKS.

The Schedule referred to in these Letters Patent and making part of the same.

To all whom it may concern:

Be it known that I, ROBERT J. JORDAN, of the city, county, and State of New York, have invented a new and useful Improvement in Piano and Sewing-Machine Locks; and I do hereby declare that the following is a full, clear, and exact description thereof, which will enable others skilled in the art to make and use the same, reference being had to the accompanying drawings, forming part of this specification.

Figure 1 is a detail view of the inner side of my improved lock, part of the cap-plate being broken away, and showing the bolt drawn back, or unlocked.

Figure 2 is the same view as fig. 1, but showing the bolt pushed forward, or locked.

Similar letters of reference indicate corresponding parts.

My invention has for its object to furnish an improvement in the construction of locks, designed especially for piano and sewing-machine locks, but equally applicable for other locks, and by means of which a neat, simple, and reliable lock is produced; and

It consists in the construction and combination of the various parts of the lock, as hereinafter more fully described.

A is the lock-plate, which is made and secured in place in the ordinary manner.

B is the sliding plate, the forward end of which is bent up at right angles, or has a flange, b', formed upon it, which said flange is slotted to receive the spiral part of the bolt C, as shown in figs. 1 and 2.

The rear, or inner end of the sliding plate B is slotted to receive the stem, or shank of the guard-plate D, the shoulders, or ends of the body of which plate rest upon the plate B, and keep it close to the lock-plate A, while being operated.

The upper part of the plate D is slotted to receive the stem, or neck of the bolt C.

The forward part of the neck of the bolt C is formed with a shoulder, of such a size and form as, when in proper position, to be received into the slot of the plate D, as shown in fig. 1; but which, when the bolt is thrown or locked, serves as a stop to prevent the bolt from being pushed back.

The forward part of the bolt C, that passes through the slot in the flange b' of the sliding plate B, is made in the form of a spiral, making a one-quarter turn, as shown in figs. 1 and 2, so that the operation of pushing the bolt C forward or back, may revolve the bolt through one-quarter of a revolution.

The head of the bolt C, that passes out through the face-plate of the lock, and through the catch-plate E, may be diamond-shaped, as shown in figs. 1 and 2, or any other convenient form, that when in one position, will pass through the hole in the catch-plate, and which,

when revolved one-quarter, cannot be withdrawn from said plate.

The edge of the sliding plate B, and the side of the bolt C, are recessed, as shown in figs. 1 and 2, so that they may be acted upon by the key, to move them back and forth.

The recesses in the plate B and bolt C are so formed, that in locking the lock, the first movement is to carry the bolt C and plate B forward together, until the head of the bolt C has passed through the catch-plate E, at which point the advance of the bolt C is stopped by the head formed upon the rear end of said bolt striking against the slotted guard-plate D. Then, as the sliding plate B is carried forward, its advance causes the bolt C to revolve one-quarter of a revolution, so that its head may catch upon the catch-plate E.

In unlocking the lock, these movements are exactly reversed, the first effect of the key being to move the plate B back, revolving the bolt C to its former position.

The bolt C and plate B are then carried back together, until the head of the bolt C has been withdrawn from the catch-plate E, and into its place in the face-plate of the lock.

F is a spring, which is pivoted to a pin attached to the lock-plate A, and one end of which rests against another pin attached to said plate.

The other end of the spring F is divided, one part resting against the bolt C, and the other part resting against the sliding plate B, as shown in figs. 1 and 2.

The object of the spring F is simply to support the sliding plate B and bolt C, and give steadiness to their movement while being operated by the key in locking and unlocking the lock.

I do not claim, broadly, a revolving bolt, provided with a cross-head, as I am aware that such have been used; but

What I claim as new, and desire to secure by Letters Patent, is—

1. The arrangement of the guard-plate D, spring F, and revolving bolt C, the latter being operated by a key, and provided with a cross-head, which, after entering the catch-plate, is turned, so that it cannot be withdrawn, except by the key, substantially as herein described.

2. The bolt C, sliding plate B b', and guard-plate D, in combination with each other, and with the lock-plate A, all operating substantially as herein shown and described, and for the purpose set forth.

The above specification of my invention signed by me, this 11th day of November, 1868.

ROBERT J. JORDAN.
